UNITED STATES PATENT OFFICE.

GORHAM T. SEABURY, OF CHEYENNE, WYOMING.

WATER OR FLUID GAGING TUBE.

No. 839,326.

Specification of Letters Patent.

Patented Dec. 25, 1906.

Application filed May 28, 1906. Serial No. 319,140.

To all whom it may concern:

Be it known that I, GORHAM T. SEABURY, a citizen of the United States of America, residing at Cheyenne, county of Laramie, and 5 State of Wyoming, have invented a new and useful Water or Fluid Gaging Tube, of which the following is a specification.

My invention relates to improvements in water or fluid gaging tubes for boilers and 10 liquid-receptacles; and the object of my invention is to provide a double-compartment water or fluid gaging tube for boilers and tanks, which compartments are arranged in such a manner relative to the water in a boiler to which the tube is attached that no matter how violent the water may boil or foam in the boiler the water in the sight-tube of my water-gage will be at 15 rest and indicate the true height of the water 20 in the boiler. I attain this object by the mechanism illustrated in the accompanying drawings, in which—

Figure 1 is a front elevation of my improved fluid-gaging tube, the lower part of 25 the front wall being cut away to show the partition between the two compartments and the holes at the lower corners of the partition, which form a communication between the compartments. Fig. 2 is a central vertical sectional view of the same. Fig. 3 is a 30 horizontal sectional view on the line 3 3 of Fig. 2. Fig. 4 is a perspective view of one of the sight-glasses, and Fig. 5 is a sectional view of a modified form of the gaging-tube.

Similar figures of reference refer to similar parts throughout the several views.

Referring to the drawings, the numeral 1 designates a water-gage tube, which I preferably construct substantially in the form of a 40 triangle in cross-section, although any other suitable form of cross-section for the tube may be used, if desired. This tube is constructed of any suitable metal and contains two vertical compartments 2 and 3, which 45 are separated from each other by a partition 4. The compartment 2 is formed in the tube along its widest side, and the partition 4 is formed parallel with it. The compartment 3 is also formed parallel with the compartment 2; but its opposite sides are beveled to 50 match the bevel of the outside of the tube. In the compartment 3 I form a plurality of sight water-indicating apertures, which extend through the sides 3 and 7 and the front 55 8, which is made with a flat surface. While any preferred number of sight-apertures may

be formed in each of the sides, I preferably form five, arranging them at equal distances apart in a vertical row along each of the opposite sides of the tube, the oppositely-arranged openings being on the same horizontal plane, and in the front I preferably place two sight-apertures, arranging them so as to locate the lower one midway between first and second pair of side inlets, while the upper one is midway between the third and fourth pair of side inlets. These sight water-indicating apertures are of two diameters and they are all alike. Consequently a description of one will apply to all of them. The first diameter 9 extends into the sides and apex end of the tube to nearly through the thickness of metal of the tube, where it terminates in a square shoulder 10, from which a smaller hole 11 extends through the metal into the compartment. 75

The entrance to the aperture 9 is threaded for a portion of its length, and an eye-ring nut 12 is provided with a hub 13, which is threaded to screw into it, and also with a wrench-receiving polygonal surface, by which it may be screwed and unscrewed into the threaded aperture, and between this eye-ring and the shoulder at the bottom of the aperture 9 I place a transparent eyepiece 14, which I preferably make of glass. This glass eyepiece preferably consists of a disk portion, from the opposite sides of which project two hub portions 15 and 16, one of which, 15, projects into the smaller diameter of the eye-aperture, and the other, 16, projects into the eye-ring, and in order to secure the eye-glass in the eye-aperture against leakage I place a rubber washer 17 on the shoulder 10 at the bottom of the aperture 9 and around the hub 15 of the glass eye and place the adjacent disk portion of the eyepiece against it. I also place a rubber washer 18 on the hub 16 and against the adjacent side of the disk portion of the eyepiece and then screw the eye-ring 100 down against the rubber washers, and thereby clamp the rubber washer and the glass eye against the shoulder 10, thus providing an easily-removable water-tight eye-sight. Through the top end of the tube I form a 105 threaded aperture 19 into the compartment 2, in which I screw a nipple 20 or other suitable fitting, which is adapted to be connected to a boiler or tank. Through the bottom of the tube I also form a threaded aperture 21 into the compartment 2, to which a nipple or other suitable pipe-fitting 22 is secured,

which is adapted to be secured to a boiler or tank. The apertures 19 and 21 are preferably arranged in the center of the chamber 2. At the bottom of the compartment 2 I form 5 two apertures 23 and 24 through the partition into the compartment 3, placing one at each side of the chamber, and at the top of the partition, in its central portion, I also form an aperture 25 through it into the compartment 10 3.

In Fig. 5 I illustrate a slight modification of the arrangement shown in the preferred construction. In this arrangement instead of making a double compartment in the tube 15 I make a tube with a single compartment 26 and with inlets 27 and 28 at its opposite ends and also provide one side of the tube with threaded apertures at its opposite ends, to which elbow-nipples are threaded at one end. 20 These elbows are provided at their opposite ends with couplings 29, which are adapted to be connected to and to hold a glass water-indicating tube 30, and this arrangement will operate similar to the double-compartment 25 tube.

The operation is as follows: The tube is connected to a boiler in the usual manner, and the water flows into the compartment 2 and through the apertures at the bottom of 30 the partition into the compartment 3, where it is visible from three angular points of view through the eye glass rings, and in case the water in the boiler is foaming or boiling it will not affect the water in the compartment 3 of the gage, which will always remain at rest, 35 while the commotion of the water will be spent and disappear in compartment 2.

Having described my invention, what I claim as new, and desire to secure by Letters 40 Patent, is—

1. In a water-gage, a water-gage triangular-shaped in cross-section, having two vertically-arranged compartments parallel with each other, and separated from one another 45 by a vertical partition, containing passages connecting the two compartments at its opposite ends, and a vertical row of transparent light-inlet eyelets in the sides and apex ends of said triangular-shaped tube, and fluid-inlet 50 apertures at the opposite ends of the compartment adjacent to said sight-eyelet com-

partment, arranged to be operatively connected to a boiler or tank.

2. In a water-gage, the combination of a water-gage triangular-shaped in cross-section, having two fluid-compartments, one of which is provided with fluid-inlet apertures at its opposite ends, and is arranged to be connected to a boiler or tank, and the other of which is provided with three rows of transparent light-inlet eyelets arranged on three different sides of said triangular-shaped tube, and means for attaching and detaching said light-eyelets to said tube, as specified. 55

3. In a water-gage, a water-gaging tube, 60 of a water-gage triangular-shaped in cross-section, having two independent compartments separated by a vertical partition and connected together at their upper and lower ends, by lateral passages through said portion, fluid-inlet apertures in the opposite ends of the compartment adjacent to the base of said triangle, provided with pipe-fittings adapted to be connected to a boiler or tank, and a plurality of transparent light-inlet eyelets in the side angle, and apex-surfaces, of said tube, arranged in rows, each eyelet of which comprises a threaded aperture extending through the shell of said tube into said chamber, a glass disk packed in said aperture, 65 and a threaded eye-ring threaded to said aperture and arranged to clamp said glass disk in said aperture, as specified. 70

4. In a water-gage, the combination with the water-gage triangular-shaped in cross-section, provided with the two compartments therein, and with the partition separating the two compartments, and the lateral fluid-connecting passages in said compartments, and the light-inlet eyelets, comprising the threaded aperture, of two diameters, the glass disk, and the rubber washers, arranged to be inserted in said apertures, with the nut-shaped threaded eye-ring arranged to clamp said glass disk, and rubber washers in said apertures, as specified. 80

In testimony whereof I affix my signature in presence of two witnesses.

GORHAM T. SEABURY
